WHITE FLUORESCENT AGENT

William W. Williams, New York, N. Y., and William H. Libby, St. Paul, Minn., assignors to General Aniline & Film Corporation, New York, N. Y., a corporation of Delaware

No Drawing. Application March 30, 1956
Serial No. 575,000

5 Claims. (Cl. 260—247.1)

The invention here presented is a new whitener in the form of a dye type of substance which is fluorescent under ultra violet to yield a brilliant bluish white fluorescence, which agent is found in the triazinostilbene series.

It is well known that cellulosic materials such as paper, cotton textiles and the like have a slight yellowish hue which, particularly in the case of textile materials, is apt to become more pronounced when the material is subjected to repeated launderings and use. Accordingly, it has long been the practice to treat many white cotton textiles, when they are washed, with a bluing substance, such as ultramarine. It has been found that the slight blue coloration thus imparted to the material compensates for the yellowish tint or similar off-white shade of the material so that it appears whiter; such bluing operations, however, result in the absorption of a measurable portion of the total visible light falling upon the treated material and, accordingly, the treated material has a slightly dull appearance.

It has recently been proposed to treat paper or cotton textiles and similar cellulosic materials with agents which, while themselves colorless, fluoresce in the blue range of the spectrum so that in daylight or other light, which includes ultra violet radiation, the fluorescence of the treating agent compensates for the slight yellowish tint or similar off-white shade, the blue being complementary to yellow. Such fluorescent agents only absorb a negligible portion of the visible light falling on the material and, accordingly, as a result of the fluorescence the treated material is much brighter as well as whiter in appearance.

While a wide variety of fluorescent agents have been suggested for treatment of fibrous materials, it has been found that for the treatment of cellulosic materials, either paper or textiles, the use of fluorescent agents which are substantive to cellulose is preferable since by the use of substantive fluorescent agents a whitening or brightening effect which is resistant to laundering is obtained.

Such substantive fluorescent agents have been applied to the material to be treated therewith either in a separate treating operation, or advantageously a small amount of the fluorescent agent may be incorporated in the soap or other detergent used for washing the textiles, and when the textile is washed with a detergent containing a fluorescent brightening agent, a small amount is picked up by the material so that after drying the material appears much whiter and brighter than untreated materials.

These fluorescent brightening agents are also useful in treating textile materials which are to be, or have been dyed or printed with discharge paste. The whites of the materials so printed with pastes containing brightening agents are much whiter than is otherwise the case.

While numerous fluorescent bleaching or brightening agents have heretofore been suggested, including diamino-stilbene sulfonic and carboxylic acids and certain acylated derivatives thereof, only a few of them have been satisfactory, particularly for use by incorporation in soap or other detergents. In order to be satisfactory for use as a brightening agent to be incorporated with soap or similar

2

detergents, the fluorescent material which is employed should be itself colorless, or nearly so, and must not stain the material. It is necessary that it have a true bluish fluorescence with no tendency toward imparting visible yellow tints to the treated fabric. It must also have a proper degree of substantivity towards the materials as too small a degree of substantivity renders it valueless as it would be removed in any rinse waters, and too high a degree of substantivity results in a gradual build-up of fluorescent agent on material during repeated launderings resulting in off-color shades. The fluorescent agent must be stable to light and not discolor on exposure. It must be stable to hypo-chlorite treatment and not discolor under such treatment, and in addition, it must fluoresce over a fairly wide pH differential, including both alkali and acid.

The present invention presents a series of compounds which have some of the characteristics of dyestuffs or pigments, which in addition show a strong bluish white fluorescence of outstanding brilliance, which compounds in addition are readily incorporated into a wide range of fabrics, fibers, felted materials and paper, to yield an outstanding whiteness in the material to which they are applied. This material is a triazinostilbene compound containing a semicarbazide group with an associated alkyl amino group. Broadly the compound has the following molecular structure:

where X is selected from the group consisting of morpholino, dimethylamino, diethylamino or di-(hydroxyethyl)-amino substituents.

This compound, and a considerable group of analogous compounds, are readily prepared by condensing 1 molecular proportion of 4,4'-diamino-2,2'-stilbene-disulfonic acid with 2 molecular proportions of cyanuric chloride. The primary condensation product can be further condensed with 2 molecular proportions of semi-carbazide hydrochloride and finally with 2 molecular proportions of morpholine, dimethylamine, diethylamine or diethanolamine.

These materials are particularly useful for application to paper or fabrics or other sheet or wrapping material to improve the whiteness thereof. They are useful when applied to fabrics by methods well known in the art since the whiteness is remarkably improved. The white background of photographic prints and diazotype prints can be improved by incorporating some of the material into the coating emulsions. By addition of the substances to discharge pastes, the whites obtained upon discharge are decidedly whiter than those discharges made in the absence of said materials. If small quantities of these materials are used in soaps or other detergents, fabrics which are washed using these formulations will be much whiter in the case of whites and much brighter in the case of colors than fabrics which are washed with ordinary soaps or detergents. These materials may be used to bleach fabrics. In such cases, the amount of bleach necessary is materially reduced and one or more steps in the normal bleaching operation may be eliminated.

Thus the product of the invention outstandingly increases the apparent whiteness of a wide range of surfacing materials by the incorporation therewith of a dye

type substance of the triazinostilbene series containing a semicarbazide group and an alkyl amine substituent.

cooled and the product is separated in the usual manner. It corresponds to the formula:

Other objects and details of the invention will be apparent from the following description.

The following examples show the preferred method of practising the invention but various modifications will be obvious to those skilled in the art.

Example I

Thirty-seven parts of cyanuric chloride are dissolved in 120 parts of acetone and poured into a mixture of ice and water. During the suspension in ice water, the temperature of the aqueous suspension should not rise above 5° C. Thirty-seven parts of 4,4'-diaminostilbene-2,2'-disulfonic acid are dissolved in 150 parts of water with the addition of enough sodium carbonate to give a neutral

20

25 The procedure of Example I was repeated up to and including the end of the secondary condensation whereupon, instead of adding 56 parts of morpholine, 142 parts of a 33% aqueous solution of dimethylamine were added and the pH increased to 7.5 to 7.8 with sodium carbonate solution. Then the mixture was heated slowly to 65° C. and maintained at that temperature for 8 hours, as before. Upon cooling and separating the product a material was obtained corresponding to the formula:

50 solution. This solution is added slowly to the cyanuric chloride suspension and at the same time a solution of sodium carbonate is added in order to keep the mixture from becoming too acid. The temperature should not rise above 5° C. during this condensation. The condensation is complete when a sample of the reaction mixture which has been acidified and treated with sodium nitrite does not develop color when treated with an alkaline solution of R salt.

When the condensation is complete, a solution of 22.4

45

55 The material which is obtained is slightly tan in color and moderately soluble in water but very slightly soluble in acetone, alcohol, ether and the like.

Example II

The procedure of Example I was repeated up to and including the secondary condensation; then instead of adding 56 parts of morpholine, 73 parts of diethylamine were added and the material neutralized and heated as before to yield a product corresponding to the formula:

parts of semicarbazide hydrochloride is added and immediately afterward a solution of 160 parts of anhydrous sodium acetate in 400 parts of water is added. The mixture is allowed to warm to room temperature and may be heated to 35-40° C. if necessary to complete the condensation. When this secondary condensation is complete, 56 parts of morpholine are added and the pH is increased to 7.5-8 with sodium carbonate solution. Then the mixture is heated slowly to 65° C. and maintained at that temperature for 8 hours. The mixture is then

70

75 The material which is obtained is slightly tan in color and moderately soluble in water but very slightly soluble in acetone, alcohol, ether and the like.

Example IV

The procedure of Example I was repeated, as before, up to and including the secondary condensation; then instead of the 56 parts of morpholine, there were added 68 parts of diethanolamine, after which, the processing

shown in Example I was repeated to yield a compound having the formula:

The material which is obtained is slightly tan in color and moderately soluble in water but very slightly soluble in acetone, alcohol, ether and the like.

It may be noted that in all of these 4 examples, the X substituent, as shown in the first structural formula, may consist of a morpholino, dimethylamino, diethylamino, or a dihydroxy ethylamino substituent.

When this material is incorporated into discharge pastes and applied to fabrics, the whites thus obtained were remarkably whiter than those obtained using ordinary discharge pastes. When this material is applied to fibers of cellulose, wool or nylon, by methods well known in the art, the white appearance of the fabric is thereby much improved.

If small amounts of this substance are added to soap or detergent and the resulting mixture is used to wash fabrics of cellulose, wool or nylon, the white materials thus washed are extraordinarily whiter in appearance and colored materials are brighter than similar materials which are washed using ordinary soaps or detergents.

white appearance of a wide variety of surface substances. While there are above disclosed but a limited number of

embodiments of the process of the invention it is possible to provide still other embodiments without departing from the inventive concept herein disclosed and it is therefore desired that only such limitations be imposed upon the appended claims as are stated therein or required by the prior art.

The invention claimed is:

1. A whitener having the composition:

where X is selected from the group consisting of morpholinyl, dimethylamino, diethylamino and di-(hydroxyethyl)-amino.

2. A whitener having the composition:

The product and process of the invention thus provide

3. A whitener having the composition:

material and procedures for outstandingly increasing the

4. A whitener having the composition:

5. A whitener having the composition:
